UNITED STATES PATENT OFFICE.

WILLIAM WIEK, OF IOLA, KANSAS.

METAL-SHEARING DEVICE.

SPECIFICATION forming part of Letters Patent No. 742,942, dated November 3, 1903.

Application filed June 30, 1903. Serial No. 163,800. (No model.)

To all whom it may concern:

Be it known that I, WILLIAM WIEK, a citizen of the United States, residing at Iola, in the county of Allen and State of Kansas, have invented a new and useful Metal-Shearing Device, of which the following is a specification.

My invention relates to metal-shearing devices of the type employed for shearing or cutting sheet or bar metal, and has for its objects to produce a device of this character of simple construction which will be efficient in operation, one in which either sheet or bar metal, or both, may be acted upon at a single operation, and one in which a direct pressure upon the movable shearing-blade will be had during the operation of the device.

To these ends the invention comprises the novel details of construction and combination of parts more fully hereinafter described.

20 In the accompanying drawings, Figure 1 is a side elevation of a metal-shearing device embodying my invention. Fig. 2 is a vertical transverse section on the line 2 of Fig. 1.

Referring to the drawings, 1 indicates the base, of any suitable construction or material, to which the frame of the machine is attached by bolts or otherwise. The frame of the machine consists of a table or support 2, from the rear end of which arises an integral head 3, or standard 3, to which latter is bolted or otherwise secured a horizontal arm 4, which overhangs and is coincident in length with the table 2.

5 indicates a fixed shearing knife or blade carried by and projecting slightly above the table or support 2, and 6 a coöperating movable knife or blade eccentrically pivoted at its rear upper corner to the arm 4, as at 7, and provided at its forward end with a semi-circular recess 8, which receives the circular head 9 of a lever 10, eccentrically pivoted, as at 11, to the forward end of arm 4 and adapted when raised and lowered to swing upon its pivot 11 and, owing to its eccentricity, 45 act upon the blade 6 for raising or lowering the latter. In this connection it is to be noted that owing to the eccentrically-pivoted head of the lever being in direct engagement with the movable blade in advance of the 50 pivotal point of the latter and above its cutting edge force or pressure applied to the lever during the operation of the device will

be transmitted directly to the blade, thus materially increasing the cutting strength of the latter. It is also to be noted that the inner 55 face of the blade 6 contacts with the outer face of blade 5 and that when the forward end of the former is elevated its cutting edges 12 and 13 will be disposed at an angle relative to their normal positions, whereby during the depression of the blade they will act with a shearing cut upon the material operated upon, and, further, that owing to the blade being eccentrically pivoted its movement will be such as to compensate for the head in its 65 movements, thus obviating liability of the head moving out of or binding in the recess.

14 designates a series of perforations formed transversely through the arm 4 beneath and slightly in rear of the pivotal point 7 of the 70 blade 6. These perforations vary in size and are designed for the reception of bar or rod metal, which will be cut or sheared by the edge 12 of blade 6 during the operation of the latter.

From the foregoing it will be seen that I produce a device of simple construction which will be efficient in operation and one which is admirably adapted for the attainment of the ends in view. It is, however, to be understood that I do not limit myself to the precise details herein shown and described, inasmuch as minor changes may be made therein without departing from the spirit or scope of the invention.

Having thus described my invention, what I claim is—

1. In a device of the class described, the combination with a table or support, of a blade carried thereby, an overhanging arm 90 sustained above the table, a movable blade pivoted adjacent to its rear end to the arm and provided at its forward end with a semi-circular recess, and an operating-lever having a circular head eccentrically pivoted to 95 the arm and in direct engagement with the semicircular recess of the blade.

2. In a device of the class described, the combination with a table or support, of a blade carried thereby, an overhanging arm 100 sustained above the table and provided with one or more perforations, a movable blade pivoted adjacent to its rear upper end to the arm and slightly above and in advance of the per-

forations in the latter, and provided at its forward end with a semicircular recess, and an operating-lever having a circular head eccentrically pivoted to the arm and in direct engagement with the semicircular recess of the blade.

In testimony that I claim the foregoing as

my own I have hereto affixed my signature in the presence of two witnesses.

WILLIAM WIEK.
